Primary Examiner — Rosemary K Tarcza*Assistant Examiner* — Nathaniel D Buckner(74) *Attorney, Agent, or Firm* — Davis & Bujold PLLC;
Michael J. Bujold(57) **CLAIM**

The ornamental design for a shuttering formwork, as shown and described.

DESCRIPTION

FIG. 1 is a perspective view of the shuttering formwork of the present invention;

FIG. 2 is a front elevation view, the rear elevation view being a mirror image thereof;

FIG. 3 is a right side elevation view, the left side elevation view being a mirror image thereof; and,

FIG. 4 is a top plan view.

The broken lines shown in the drawings depict features that form no part of the claimed design.
